[57] **ABSTRACT**

Perfume compositions are provided which are based upon certain cycloalkylidenebutanals. The perfume compositions comprising the subject cycloalkylidenebutanals.

3 Claims, No Drawings

PERFUME COMPOSITIONS

This is a continuation of application Ser. No. 8729, filed Feb. 4, 1970 now abandoned.

This invention relates to new perfume compositions and compounds which are suitable for use as an active ingredient in perfume compositions.

It has long been recognized in the art that various organic compounds are suitable for use as the active ingredient in perfumes.

An object of this invention is therefore to provide new perfume compositions.

A further object of this invention is to provide novel compounds which can impart a pleasing scent and accordingly can be used in perfume compositions.

The objects of this invention are accomplished by the discovery of certain novel cycloalkylidenebutanals of the following general formula:

wherein

A together with the carbon atoms C₁, C₂ and C₃ forms a monocyclic or polycyclic aliphatic radical, each of R₁, R₂, R₃ and R₄ is independently hydrogen or an alkyl radical of from 1 to 5 carbon atoms, and when A represents ethylene or propylene at least one of R₁, R₂, R₃ and R₄ is an alkyl radical of from 1 to 5 carbon atoms.

According to a preferred embodiment of the invention, the total number of carbon atoms represented in formula (I) is from 11 to 28.

According to a still more preferred embodiment of the invention, the total number of carbon atoms represented in formula (I) is from 11 to 18 carbon atoms.

The compounds of the formula (I) have been discovered to possess a strong odor which makes them particularly suited for use in perfume compositions. These compounds may be mixed with other components commonly found in perfumes, such as aromatic components, in order to obtain specific, characteristically widely divergent perfume compositions, imparting in general a fruity-green scent with a distinct scent of a very floral muguet. The compounds of the present invention may be used therefore in compositions such as cosmetics, soaps, soap powders, detergents, toilet waters, lotions, aerosols, creams, powders and any other composition to which the distinctive odor of the compounds is desired.

It is quite unexpected that the compounds of the present invention were found to possess the desirable properties of the muguet scent. Thus, although it is known that a few γ , δ unsaturated carbonyl compounds can be used as perfumes, it was unexpectedly discovered that cyclic aldehydes of Formula (I) possess the desirable muguet odor.

The compounds of Formula (I) may be prepared in several ways.

As a first method of synthesizing the subject compounds of Formula (I), spirohydropyrans are heated over a copper catalyst at a temperature ranging between 200° C and 400° C. This conversion may be carried out continuously.

The starting material spirohydropyrans may be represented by the following formula:

10 wherein

A, R₁, R₂, R₃, and R₄ have the previously assigned meanings.

As a second method of synthesizing the compounds of Formula (I), vinylcyclanoles and a vinyl ether are heated in the presence of a catalytic amount of acid at a temperature ranging from 50° C to 150° C. A variation of this method has been described in Dutch Patent Application No. 295,084, as well as in Bull. Soc. Chim. de France, 1964, pages 2618-2635.

15 20 The vinylcyclanoles used to produce the compounds of Formula (I) have the following formula:

25 wherein

A, R₁, R₂, R₃ and R₄ have the previously assigned meanings.

The vinyl ether has the following structure

30 35 The R group is not critical to the nature of the products of the invention as it is split off during the reaction. It may be, for example, a lower alkyl group. Thus, a typical vinyl ether of Formula (IV) is vinylethyl ether.

40 45 The following examples are illustrative of the preparation of compounds within the scope of the invention.

EXAMPLE I

Preparation of 4-(tricyclodecylidene)-butanal-1 (First Method)

50 55 60 65 70 75 80 85 90 95 100 g of spiro-6,1'-tricyclodecyl-4,5-dihydropyran

is passed through a glass reactor tube filled with 100 g of bronze powder (B.D.H. quality) mixed with 10 g of hyflo (filtering aid of Johns-Manville Sales Corp., New York, U.S.A.) for five hours at a temperature of 300° to 320° C. The reaction product is condensed in a cooler connected to the reactor and consists of:

Having described the preparation of representative compounds within the scope of the invention, the following illustrative examples are presented to show actual compositions prepared according to the claimed invention.

EXAMPLE VI

EXAMPLE VI

Lilas composition

50 g	of cinnamie alcohol
40 g	of heliotropin
300 g	of phenylethanol
10 g	of laurylaldehyde, 10% in diethylphthalate
5 g	of 4-(tricyclodecylidene)-butanal-1
20 g	of methyl-alpha-nonylenate
20 g	of iso-eugenol
40 g	of anisaldehyde
75 g	of alpha-amylcinnamicaldehyde
100 g	of benzyl acetate
40 g	of indole, 10% in diethylphthalate
300 g	of terpineol
1.000 g	

EXAMPLE VII

EXAMPLE VII

Phantasy perfume

20 g	of styrax resinoid
20 g	of dimethylcarbonyl acetate
80 g	of benzyl acetate
15 g	of oil of lemon Messina
5 g	of laurylaldehyde, 10% in diethylphthalate
15 g	of methylnonylacetaldehyde 10% in diethylphthalate
10 g	of 4-(decalinylidene-2') butanal-1
10 g	of 2-heptyltetrahydrofuran
25 g	of amyl salicylate
50 g	of ylang-ylang oil
50 g	of geranium oil Bourbon
150 g	of alpha-ionone
50 g	of benzyl salicylate
20 g	of indole, 10% in diethylphthalate
150 g	of hydroxycitronellal
150 g	of linalool
150 g	of linalyl acetate
30 g	of phenylethyl acetate
1.000 g	

EXAMPLE VIII

EXAMPLE VIII

Soap perfume
10 g
10 g
30 g
5 g
100 g
10 g
100 g
150 g
150 g
50 g
50 g
140 g
80 g
10 g
5 g
40 g
50 g
1.000 g

of dimethylbenzylcarbonyl acetate
of iso-camphylcyclohexanol
of coumarin
of 1,1,3,4,4,6-hexamethyl 7-acetyltetralin
of benzyl acetate
of 4-(tricyclodecylidene)butanal-1
of oil of thyme
of Lavandin oil
of 4-tert butylcyclohexyl acetate
of terpineol
of citronellol
of geraniol
of phenylethanol
of alpha-amyl cinnamic aldehyde
of 2,4-dimethyl 6-butyl 2,6-dihydropyran
of undecylene aldehyde
of amyl salicylate
of hydroxycitronellal

EXAMPLE IX

EXAMPLE IX

Phantasy perfume
5 g
60 g
40 g
20 g
5 g
15 g
5 g
10 g
20 g
20 g
60 g
50 g
180 g
260 g
270 g
1.000 g

of heliotropin
of cinnamic alcohol
of benzyl acetate
of methyl alpha-nonylenate
of ylang-ylang oil
of 4-(cyclododecylidene) butanal-1
of metnhyionon
of benzyl salicylate
of nerolidol
of linalool
of alpha-hexyl cinnamic aldehyde
of nerol
of citronellol
of hydroxycitronellal

What is claimed is:

1. A perfume composition comprising conventional perfume constituents and an effective amount of 4-(tricyclodecylidene)-butanal-1 to impart a fruity-green, muguet-like note.
2. A perfume composition comprising conventional perfume constituents and an effective amount of 4-(tricyclodecylidene)-butanal-1 to impart a fruity-green, muguet-like note.
3. A perfume composition comprising conventional perfume constituents and an effective amount of 4-(decalinylidene-2')-butanal-1 to impart a fruity-green, muguet-like note.
